UNITED STATES PATENT OFFICE.

ARTHUR LOUIS WALTERS, OF INDIANAPOLIS, INDIANA, ASSIGNOR TO ELI LILLY AND COMPANY, OF INDIANAPOLIS, INDIANA, A CORPORATION OF INDIANA.

DRESSING FOR WOUNDS.

Application filed July 5, 1921. Serial No. 482,305.

To all whom it may concern:

Be it known that I, ARTHUR L. WALTERS, a citizen of the United States, residing at Indianapolis, in the county of Marion and 5 State of Indiana, have invented a new and useful Dressing for Wounds, of which the following is a specification.

It is the object of my invention to provide a convenient dressing for wounds, especially 10 adapted for first-aid treatment, which dressing carries its own medicament in a container within itself, and which medicament may be caused to saturate the dressing substantially instantly when desired, so that 15 the dressing may be made immediately ready for application to the wound, even by one entirely unskilled.

The accompanying drawing illustrates my invention: Fig. 1 is a perspective view of 20 the complete package containing the dressing; Fig. 2 is an end elevation of the stitched gauze strip which forms the outer part of the dressing proper; Fig. 3 is a perspective view of the strip of absorbent 25 cotton with the medicament-containing ampoule in position thereon ready to be rolled therein; Fig. 4 is a perspective view of the roll of absorbent cotton containing the ampoule in place in the gauze strip; 30 and Fig. 5 is a sectional perspective view showing the complete dressing in its containing envelope.

The dressing proper, which is relatively flat, has an outer layer of absorbent gauze 35 10, preferably formed from a strip of suitable width folded on itself to form several layers, which are stitched together by a few stitches 11, conveniently parallel to the folds, thus leaving two free-edge flaps 12 40 which may be separated for assembly or laid together when assembled. The medicament to be used is put in a long slender container 13, preferably slightly shorter than the width of the gauze strip 10, and 45 this container is rolled up in a strip of absorbent cotton 14, which when rolled with the container 13 within it is placed between the two flaps 12 and against the stitching 11, as indicated in Fig. 4. The two flaps 50 are then laid together to enclose the container-holding roll of cotton, and the whole substantially flat dressing is placed flatwise in a suitable envelope 15, conveniently made of impervious paper and also substantially 55 flat, to keep the dressing clean and prevent

staining of the fingers. The envelope preferably has printed upon it the legend "Crush here first" which legend is so located that the ampoule 13 lies directly beneath it. The complete dressing, either with 60 or without the envelope, is flexible transversely of the container 13, for it is many times as wide as is such container. This dressing can quite readily be stacked up and packaged with other like dressings. 65

The medicament used in the container may be anything desired; probably the most generally suitable one is tincture of iodine. The container itself is conveniently made of glass, hermetically sealed, but while this 70 is perhaps the most convenient material it is not essential that glass be used, as any other suitable container may be used which permits the discharge of the medicament when pressed or broken. 75

When the dressing is to be used, it is first crushed along the line of the container, as indicated by the legend "Crush here first"; and, the envelope 15 having been opened as by tearing it along the 80 dotted line 16, the dressing proper is removed from the envelope and immediately laid upon the wound. The crushing of the container 13 permits the iodine or other medicament to escape therefrom and to 85 saturate the cotton 14 and gauze 10. This gauze 10 and the cotton 14 effectively prevent any particles of the broken glass container from getting free from the dressing and into the wound. 90

I claim as my invention:

1. A dressing for wounds, comprising a plurality of layers of absorbent material superposed to form a flexible, flat pack, and a frangible medicament container among 95 such layers.

2. A dressing for wounds, comprising a plurality of layers of absorbent material superposed to form a flexible, flat pack of great length and width relative to its thickness, a frangible medicament container among such layers, and a covering of absorbent cotton around said container, said pack having a pair of flaps extending from 100 said container in opposite directions. 105

3. A dressing for wounds, comprising a plurality of layers of absorbent material superposed to form a flexible, flat pack, a frangible medicament container among such 110 layers, said layers of absorbent material be-

ing stitched to locate said container in proper position.

4. The combination with a dressing as set forth in claim 1, of an envelope in which such dressing is enclosed to hold its parts together and in place and to insure its being kept clean while said medicament container is being broken.

5. A dressing for wounds, comprising a plurality of layers of absorbent material

superposed to form a flexible, flat pack, and a frangible medicament container among such layers, said pack being adapted to be grasped by the hands on opposite sides of said container.

In witness whereof, I have hereunto set my hand at Indianapolis, Indiana, this 30th day of June, A. D. one thousand nine hundred and twenty-one.

ARTHUR LOUIS WALTERS.
